Patented July 2, 1918.

UNITED STATES PATENT OFFICE.

AARON H. WOLFF, OF NEW YORK, N. Y.

HEATING APPARATUS.

1,270,910.

Specification of Letters Patent.

Patented July 2, 1918.

Application filed August 13, 1917. Serial No. 185,847.

To all whom it may concern:

Be it known that I, AARON H. WOLFF, a citizen of the United States, residing at the borough of Manhattan, city, county, and 5 State of New York, have invented certain new and useful Improvements in Heating Apparatus, of which the following is a specification, reference being had therein to the accompanying drawings, which form 10 a part thereof.

My invention relates to heating apparatus, and more particularly to a type thereof containing a plurality of radiator elements, each of which has therein a gas or similar 15 burner. The general type of apparatus to which my invention relates is old and well known in the art, the purpose of my invention being to prevent the discharge of noxious gases from such an apparatus into a 20 room either as the result of a delayed or imperfect ignition of the gas at the various burners, or as the result of imperfect combustion due to an inadequate or improperly controlled circulation of air within the sev- 25 eral elements, or to the impingement of a flame, from any burner upon the metal portion of the different elements, by reason of the formation of said elements, or variation in the flame due to drafts or uncontrolled 30 air currents about the burners.

In an apparatus made in accordance with my invention, the several heat radiating elements are so constructed and so united, as to be completely closed at the bottom there- 35 of, while being in communication with each other in a manner to secure substantial uniformity in the distribution of the heat throughout all of the elements while permitting the use of a supply conduit for gas, 40 common to all of said elements. The manner of connecting the several elements is such that a large chamber, passing through the assembled structure is formed, the walls of said chamber being spaced, at all points, 45 sufficiently away from the burners to mini- 50 mize any likelihood of the flame or flames impinging upon any metal portion of the several elements. The walls forming said chamber are so formed as to space the sev- 55 eral elements apart in a manner to facilitate the proper circulation of air through each element while so baffling, or directing, the air flowing through one element as to prevent the passage thereof to an adjoining 60 element in a manner to deflect the flame jet

and cause it to impinge upon said walls. This baffling effect, however, is of secondary importance since each of the elements is provided with an air inlet and air outlet so disposed in relation to each burner, as to minimize likelihood of any side deflection of the jet in said element. 60

The provision of the chamber above described, also permits the utilization of an igniting device common to all of the burners 65 in the assembled apparatus which lighting device is normally so positioned when not in use as to be out of the range of the flame jets from the several burners while being readily brought to the operative position to 70 permit the simultaneous ignition of the gas emerging from all burners, at a single point of this lighting device. This device is so constructed in the assembled apparatus as to prevent the admission of air through the 75 lighting port while the apparatus is in operation, and prevent the channel member used for transmitting flame to the gas emerging from the separate burners, from remaining accidentally in a position where 80 the flames will impinge thereon. By using a structure including a lighting device for the purposes above referred to, I not only secure convenience in the lighting of the burners in the several elements, but avoid 85 an accumulation of gas within, and its es- 90 cape from, the apparatus, prior to the ignition of all of the burners, such as would necessarily follow from admitting gas to the apparatus without confining and controlling 95 the initial flow of gas from the several burners in a manner to permit this gas to be utilized for lighting purposes. 100

I also provide means by which the pipe carrying the several burners, may be quickly 95 and accurately positioned within the cham- 105 ber formed adjacent the bottom of, and com- mon to, the several elements or sections, which means will also prevent the displace- ment of the burners in installing the ap- 100 paratus.

The invention consists in the novel fea- 105 tures of construction and combination of parts hereinafter set forth and described and more particularly pointed out in the claims hereto appended.

Referring to the drawings,

Figure 1 is a side view, partly in eleva- 110 tion and partly in section, of an apparatus embodying my invention;

Fig. 2 is a section on the line 2—2 of Fig. 1;

Fig. 3 is a section on the line 3—3 of Fig. 1; and

5 Fig. 4 is a perspective view of a portion of the channel plate for simultaneously igniting all of the burners.

In the accompanying drawings, I have shown a four element, sectional radiator 10 consisting of two end sections $a-a^3$ and two intermediate sections $a'-a^2$. Each of these sections preferably comprises two side plates formed from sheet steel and permanently united by welding or in any other desired 15 or approved manner. In form each of the elements or sections is such as to afford a large radiation surface, one outside dimension of each element being very much greater than the other, thus presenting a high, narrow 20 row chamber which will insure the heating gases being brought into sufficiently close proximity to the metal to cause the heat of said gases to be readily and constantly transferred to the metal of the element.

25 The construction of each end section or element is substantially alike and differs from the intermediate sections merely in the addition of supporting legs b and in forming the nipple c so as to afford a proper bearing for the ends of the tie-bolt c' holding the upper portion of each element in the assembled apparatus in the proper position relative to every other element.

Any desired number of intermediate sections 35 may be employed each of which will be similar to every other, but will differ in the respects above noted from the end elements or sections. The description of one of these sections will, therefore, be entered 40 into, similar reference letters indicating similar parts upon the different sections.

Slightly above the bottom of each section, I form a large opening in each side plate, the metal of said plate adjacent said opening 45 being turned or formed outwardly at substantially right angles to the surrounding portions of the plate, the edge of said metal being turned inwardly of the opening, to form a flange to facilitate the uniting of 50 adjacent elements or sections adjacent the bottom thereof. The outwardly turned portion, which may be termed a "distance ring," is indicated at d and the flange thereon at d' . The bolts passing through the flanges 55 are indicated at d^2 . The opening within the rings d is substantially elliptical with the major axis extending vertically. Adjoining elements or sections are in communication 60 through the opening within the rings d thus forming in the entire lower portion of the assembled apparatus a continuous chamber in which the various burners are situated. The portion of each of the elements a to a^3 above the rings, constitutes a 65 dome adapted to receive the heated gases.

Adjacent the top of each element or section are the oppositely disposed nipples e each having an inturned bearing flange e' , which nipples serve as distance pieces adjacent the top of the several elements or sections and 70 are all in axial alignment so as to permit the tie-bolt c' to pass through all of said nipples securing the various elements or sections together adjacent the top thereof. Extending from end to end of the apparatus is 75 a pipe f carrying a plurality of burners f' , a burner being positioned directly below the dome formed by the portion of each element or section above the ring d . Preferably, I employ burners of the fantail type, 80 although, any desired form of burners may be used, it being desirable, however, to so set each burner as to have the flare of the flame extend in the direction of the greater horizontal dimension of the gas dome or of 85 the element with which said burner is associated.

To permit accuracy in the positioning of the burners, and avoid likelihood of their 90 being displaced when installing the apparatus, I mount the opposite ends of the pipe f in a fitting adapted to seat upon the outer rings d of each end section, and to be firmly secured thereto. The ends of the pipe f are permanently secured to these fittings and the 95 coupling for a flexible gas tube or other gas connection with the pipe f , is secured to this fitting instead of directly to the end of the pipe f . This fitting comprises a plate g 100 adapted to conform to the inside of the outer plate of the respective end sections or elements $a-a^3$ the lower edge of this fitting conforming to the curvature of the ring d . Carried by the plate g are offsets lugs g' having bolt openings therein. These lugs 105 bear upon the inside of the outer plate of said sections respectively and are secured thereto by means of rivets or bolts as desired. The plate g is also provided with a nipple g^2 extending beyond the ring d . The 110 pipe f is suitably fitted to the inner end of the nipple g^2 by means of ordinary screw threads while the outside of the nipple g^2 is used as a means for attaching a suitable 115 coupling g^3 or an ordinary cap g^4 , to said fitting. By this means it is impossible for the pipe f and its various burners to be turned when installing an apparatus, since the end fittings carried by said casing take up any stresses which, were it not for the 120 provision of this means preventing the turning of the pipe, would be transmitted to said pipe.

The opening within the outer rings d of the end elements or sections $a-a^3$ are closed 125 by caps $h-h'$ having openings therein through which the nipple g^2 projects.

To insure the proper circulation of air within the chamber near the bottom of the assembled apparatus, which chamber is com- 130

mon to all of the elements or sections, as well as in the individual domes above said chamber, I provide an air inlet below the pipe f and an air outlet adjacent the top of each 5 dome. To minimize any tendency toward a side deflection of the flame from the burner, I employ a plurality of air inlet openings i upon opposite sides of each burner, or in each of the side plates of each element or 10 section, so as to secure the admission of air upon opposite sides of each burner. If desired, the air outlet may consist of a plurality of openings j adjacent the top of each dome in each side plate, although, this is 15 not essential so long as the proper relative capacity of the air inlet openings i and of the outlet openings j , is maintained. By locating the various openings i below the rings d , I secure a baffling effect by the side 20 walls adjacent said rings and by the flanges d' , so that while air is permitted to pass freely through the rings d , the direction of flow will ordinarily be at an angle which will not tend to deflect the flame from the 25 burner of the adjacent element or section.

To insure a substantially simultaneous ignition of the gas emerging from the several burners f' , I provide a movable channel plate k normally positioned away from the several 30 burners while being adapted to be brought over said burners to confine the gas emerging therefrom and convey it to an ignition port at some point in the apparatus, so that the initial flow of gas will be confined 35 within the channel in the plate, and be utilized for conveying a flame to each of the burners. The plate k and the actuating means therefor are so constructed as to automatically maintain this plate away from 40 the jet openings in the burners. Said actuating means preferably includes a closure for the ignition port.

In the accompanying drawings, I have 45 illustrated a simple and effective manner of mounting and controlling the plate k which consists of end brackets k' — k^2 having openings therein by means of which said brackets are pivotally mounted upon the pipe f . These brackets are connected to the plate 50 k by a slot and screw connection, as shown, to insure the proper adjustment of the plate. The plate k is provided with weighted sections k^3 adapted to normally overbalance the plate and cause it to drop in the position 55 indicated in the dotted lines in Fig. 2. Said plate k is provided with a channeled extension k^4 , the channel of which leads from the channel in said plate and terminates adjacent a suitable opening in one wall of the 60 apparatus. As a matter of convenience, I prefer to cut away the portion of two adjoining rings d and close the opening thus formed by a fitting m having an opening or port m' adjacent the end of the extension k^4 . 65 Hinged to said fitting m is a closure n hav-

ing a lug n' thereon, said closure being operatively connected with the plate k by means of the link or connecting rod o pivotally connected with said lug and with the extension k^4 . The extension k^4 is arranged 70 substantially midway between the ends of the plate k , thus insuring uniformity in the rate of transmission of the flame to the burners of the apparatus. This, however, is merely a matter of convenience and is not 75 essential to the invention.

To prevent the plate k being brought to and remaining upon a vertical center above the burners f' , I provide the brackets k' — k^2 with a tongue k^5 which is adapted to engage 80 a stop pin g^5 carried by the plate g .

The operation of the herein described apparatus is substantially as follows:—

When an apparatus is being constructed, any desired number of elements or sections 85 may be incorporated therein, it being merely essential that the pipe f shall be of a length to permit a burner f' to be positioned directly below the dome of each element or section. The manner of assembling an apparatus made in accordance with my invention 90 is apparent from the foregoing description, it being merely necessary to point out that when so assembled, the entire lower portion adjacent, and for a considerable distance above each of the burners, is entirely free of obstruction of any kind, either directly above the burners or above and at either side thereof. This condition is presented in the outer plates of the end sections 95 100 also since the caps h — h' are spaced well away from the burners. It is to be noted that each of the domes leading from the chamber thus formed, is free of obstruction excepting the tie-bolt e' adjacent the top of 105 said dome which is sufficiently removed from the burner to avoid the formation of a carbon, or soot, deposit thereon.

This construction facilitates a more perfect combustion of the gas discharged from 110 the several burners f' and avoids fouling of the radiating surfaces within the apparatus as well as the discharge of noxious gases through the air outlets j . By arranging the air inlet openings below each of the rings d 115 upon opposite sides of each element or section, I secure a substantially direct vertical flow of air and insure the delivery of a sufficient volume thereof about each burner to properly promote combustion while at the same 120 time avoiding the flickering of the flame in a manner which would tend to cause a flame even of illuminating gas, to smoke.

When it is desired to light the burners in the apparatus, it is merely necessary to turn 125 on the gas and raise the closure n . The raising of the closure oscillates the plate k and brings the channel therein directly above each of the burners. As the gas from the burners impinges upon the plate within this 130

channel, it flows through this channel to the extension k^4 and from the end of the channel in this extension toward the port m' in the fitting m . By presenting a lighted match 5 at this port, the gas will be ignited at this point and the flame will be conveyed directly over each of the burners in a manner to ignite the gas coming therefrom. The position of the plate k above the several burners f' not only furnishes an ignition charge 10 in the manner above referred to, but prevents the escape of gas within the chamber toward the bottom of the apparatus and within the several domes, thus avoiding likelihood of the escape of gas. When it is 15 necessary to cause the gas to flow into the apparatus until a sufficiently rich mixture is secured to permit ignition at the port, without the use of the plate k , the air in the room will be sufficiently vitiated and the gas within the apparatus will be burned in a manner to foul the apparatus. Substantially instantaneously with the ignition of the gas at the port m' , the closure n may be released, the 20 weight of this closure and of the overbalancing weights k^4 upon the plate k , automatically removing the said plate from above the burners and presenting a clear field for the flame jets. 25

30 By having each of the elements or sections completely closed at the bottom, the floor underneath the apparatus is protected from any dirt which may have accumulated in the apparatus, as well as from the heat of the several burners. The tongue k^5 and the stop pin g^5 limit the movement of the plate k and prevent its being positioned so that it will not automatically close when the closure n is released. 35

40 It is essential in an apparatus made in accordance with my invention, that a burner be provided below each heat dome in order to secure high efficiency in the apparatus. By providing for proper and adequate circulation of air within the chamber adjacent the bottom of the apparatus, and through the several domes, I secure a sufficiently perfect combustion of the gas. High efficiency in the apparatus is also secured by reason of 45 the utilization of substantially all of the heat units developed therefrom the radiation of this heat from the several elements or sections and utilization of the heated gases emitted from the outlet opening. The degree of perfection in the combustion of the 50 gases avoids the likelihood of vitiation of the air in a room by noxious gases flowing from the apparatus.

It is not my intention to limit the invention 60 to the precise details of construction shown in the accompanying drawings, it being apparent that such may be varied without departing from the spirit and scope of the invention.

65 Having described the invention what I

claim as new and desire to have protected by Letters Patent, is:—

1. A heating apparatus embodying therein a plurality of elements or sections, having registering openings in the side walls 70 adjacent the bottom thereof, rings about said openings whereby said elements or sections are spaced apart and a continuous chamber common to all of said elements or sections having a plurality of upwardly extending 75 unobstructed domes is formed, closure means for the opposite ends of said chamber, a feed pipe common to all of said elements or sections adjacent the bottom of said chamber, a plurality of burners carried by said pipe, 80 one of said burners being positioned below each of said domes, and said rings being spaced away from said burners sufficiently to prevent the flame therefrom impinging upon the material of any element or section, 85 each of said elements having draft openings below the burner therein and adjacent the top thereof, and means securing all of said elements or sections together in a unitary structure. 90

2. A heating apparatus embodying therein a plurality of elements or sections, each of which is closed at the top and at the bottom thereof, said elements or sections having registering openings in the side walls there- 95 of, rings about said openings whereby said elements or sections are spaced apart and a continuous chamber common to all said elements or sections having a plurality of upwardly extending unobstructed domes is 100 formed, closure means for the opposite ends of said chamber, a feed pipe common to all said elements or sections, adjacent the bottom of said chamber, a plurality of burners carried by said pipe, one of said burners 105 being positioned below each of said domes, and said rings being spaced away from said burners sufficiently to prevent the flame therefrom impinging upon the material of any element or section, each of said ele- 110 ments or sections having an air inlet intermediate said ring and the closed bottom, and an air outlet adjacent the top, thereof, and means securing all of said elements or sections together in a unitary structure. 115

3. A heating apparatus embodying therein a plurality of elements or sections each of which is closed at the top and at the bottom thereof, said elements or sections having registering openings in the side walls there- 120 of, rings about said openings whereby said elements or sections are spaced apart and a continuous chamber common to all said elements or sections having a plurality of upwardly extending unobstructed domes is 125 formed, closure means for the opposite ends of said chamber, a feed pipe common to all said elements or sections, adjacent the bottom of said chamber, a plurality of burners carried by said pipe, one of said burners be- 130

ing positioned below each of said domes, and said rings being spaced away from said burners sufficiently to prevent the flame therefrom impinging upon the material of 5 any element or section, each of said elements or sections having air inlets through the side walls thereof below and on opposite sides of the burner therein, and an air outlet adjacent the top thereof, and means securing 10 all of said elements or sections together in a unitary structure.

4. A heating apparatus embodying therein a plurality of elements or sections, having registering openings in the side walls adjacent 15 the bottom thereof, rings about said openings whereby said elements or sections are spaced apart and a continuous chamber common to all of said elements or sections having a plurality of upwardly extending 20 unobstructed domes is formed, closure means for the opposite ends of said chamber, a feed pipe common to all of said elements or sections adjacent the bottom of said chamber, a plurality of burners carried by said pipe, 25 one of said burners being positioned below each of said domes and said rings being spaced away from said burners sufficiently to prevent the flame therefrom impinging upon the material of any element or section, each 30 of said elements having a plurality of small air inlets through the side walls thereof below and on opposite sides of the burner therein, and a plurality of small air outlets opening through the walls thereof adjacent 35 the top thereof and upon opposite sides of the element, and means securing all of said elements or sections together in a unitary structure.

5. A heating apparatus embodying therein a plurality of elements or sections having 40 registering openings therein forming a continuous chamber adjacent the bottom thereof, the side wall of said chamber having an ignition port intermediate the ends 45 thereof, means uniting said elements or sections, a feed pipe common to all of said elements or sections adjacent the bottom of said chamber, a plurality of burners carried by said pipe, one of said burners being positioned 50 in each of said elements or sections, a movable member adapted to be positioned above all of said burners and to accumulate the gas emerging therefrom and discharge it adjacent said ignition port, a pivotal 55 closure for said ignition port, and operative connection between said closure and said movable member.

6. A heating apparatus embodying therein a plurality of elements or sections having 60 registering openings therein forming a continuous chamber adjacent the bottom thereof, the side wall of said chamber having an ignition port intermediate the ends thereof, means uniting said elements or sections, a 65 feed pipe common to all of said elements or

sections adjacent the bottom of said chamber, a plurality of burners carried by said pipe, one of said burners being positioned in each of said elements or sections, an oscillatory channel plate pivotally mounted adjacent 70 said burners and adapted to be positioned above all of said burners and to accumulate gas emerging therefrom and discharge it adjacent said ignition port, a pivotal closure for said ignition port, and operative connections between said closure and said channel plate.

7. A heating apparatus embodying therein a plurality of elements or sections having registering openings forming a continuous 80 chamber adjacent the bottom thereof, the side wall of said chamber having an ignition port intermediate the ends thereof, means uniting said elements or sections, a feed pipe common to all of said elements or sections 85 adjacent the bottom of said chamber, a plurality of burners carried by said pipe, one of said burners being positioned in each of said elements or sections, an oscillatory channel plate pivotally mounted adjacent said burners and adapted to be positioned above all of said burners and to accumulate the gas emerging therefrom and discharge it adjacent said ignition port, a pivotal closure for 90 said opening and operative connections between said closure and said plate, said chamber plate and said closure being so weighted as to maintain said closure normally closed, whereby said plate may be positioned above said burners when said closure is opened and 100 will automatically return to position to one side of said burners when said closure is released.

8. A heating apparatus embodying therein a plurality of elements or sections having 105 registering openings therein forming a continuous chamber adjacent the bottom thereof, the side wall of said chamber having an ignition port intermediate the ends thereof, means uniting said elements or sections, a 110 feed pipe common to all of said elements or sections adjacent the bottom of said chamber, a plurality of burners carried by said pipe, one of said burners being positioned in each of said elements or sections, brackets 115 pivotally mounted adjacent the opposite ends of said pipe, a channel plate carried by said brackets having a channeled extension thereon projecting toward, and terminating adjacent, said ignition port when said plate 120 is positioned above said burners, whereby gas emerging from said burners is accumulated and discharged adjacent said opening, a pivotal closure for said opening and operative connections between said closure and 125 said plate, said channel plate and said closure being so weighted as to maintain said closure normally closed, whereby said plate may be positioned above said burners when said closure is opened and will automatically 130

cally return to position to one side of said burners when said closure is released.

9. A heating apparatus embodying therein a plurality of elements or sections, having 5 registering openings in the side walls, adjacent the bottom, thereof, rings about said openings whereby said elements or sections are spaced apart and a continuous chamber common to all of said elements or sections 10 having a plurality of upwardly extending domes is formed, a feed pipe common to all of said elements or sections, fittings to which the opposite ends of said pipe are firmly connected, means securing said fittings to the outer wall of the end elements or sections respectively whereby said fittings and said pipe are held against rotation and said pipe is supported adjacent the bottom 15 of said chamber, a plurality of burners carried by said pipe, one of said burners being positioned below each of said domes and said rings being spaced away from said burners sufficiently to prevent the flames therefrom impinging upon the material of any element 20 or section, and means securing all of said elements or sections together in a unitary structure.

10. A heating apparatus embodying therein a plurality of elements or sections having 30 registering openings in the side wall, adjacent the bottom, thereof, rings about said openings whereby said elements or sections are spaced apart and a continuous chamber common to all of said elements or sections 35 having a plurality of upwardly extending domes is formed, a feed pipe common to all of said elements or sections, a fitting comprising a plate adapted to seat upon the outer rings of each of said end elements or 40 sections, a nipple carried by said plate and adapted to project through and beyond said ring, means whereby each of said plates may be secured to the outer wall of said elements or sections adjacent said opening, said pipe

being mounted within said nipple whereby 45 said fitting in said pipe is held against rotation and said pipe is supported, adjacent the bottom of said chamber, a plurality of burners carried by said pipe, one of said burners being positioned below each of said 50 domes and said rings being spaced away from said burners sufficiently to prevent the flame therefrom impinging upon the material of any element or section, means securing all of said elements or sections together 55 in a unitary structure, and closure plates for the openings within said end rings respectively, each of said closure plates having an opening therethrough through which said nipples project whereby said pipe may be 60 connected with a source of fuel supply through one of said nipples.

11. A heating apparatus embodying therein means forming an elongated chamber, the wall of which chamber has an ignition port 65 therein intermediate the ends thereof, a plurality of alined burners within said chamber, a movable member within said chamber normally positioned to one side of said burners, a closure for said ignition port and operative connections between said closure and said movable member, whereby said member may be brought above said burners, said member having a channel therein terminating adjacent said opening, when said member is above said burners, whereby when said member is brought above said burners, the gas emerging from said burners will be accumulated by said member and discharged 70 adjacent said opening.

In witness whereof, I hereunto affix my signature in the presence of two subscribing witnesses, this 28th day of July, 1917.

AARON H. WOLFF.
